UNITED STATES PATENT OFFICE.

CHARLES J. LONG, OF PHILADELPHIA, PENNSYLVANIA, ASSIGNOR TO ANDREW'S MILL COMPANY, OF PHILADELPHIA, PENNSYLVANIA, A CORPORATION OF PENNSYLVANIA.

PROTECTOR MECHANISM FOR LOOMS.

1,296,676.

Specification of Letters Patent. Patented Mar. 11, 1919.

Application filed July 28, 1917. Serial No. 183,217.

To all whom it may concern:

Be it known that I, CHARLES J. LONG, a citizen of the United States, and a resident of the city of Philadelphia, county of Philadelphia, State of Pennsylvania, have invented certain new and useful Improvements in Protector Mechanism for Looms, of which the following is a specification, reference being had to the accompanying drawings.

My invention relates to improvements in protector mechanism for looms wherein a plurality of shuttle boxes and a plurality of shuttles are employed and wherein the shuttles are selected and projected across the shuttle race of the lay and through the separated warp threads.

In the operation of looms of this character, it sometimes happens that two shuttles appear in registry with the respective ends of the shuttle race, and that when this happens a collision between the two shuttles takes place during the operation of the loom which results in breaking many of the warp threads.

The object of my invention is to overcome this objection by the provision of a novel, simple and efficient means for automatically stopping the operation of the loom when two shuttles appear in registry with the respective ends of the shuttle race and before any collision between them occurs.

With this object in view, my invention consists in the novel construction and combinations of elements hereinafter described and claimed.

In the accompanying drawings, illustrating my invention:

Figure 1 is a side view of a portion of a loom having my invention applied thereto.

Fig. 2 is a front view thereof.

Fig. 3 is a sectional plan thereof.

Fig. 4 is a sectional detail, enlarged, showing a portion of the mechanism operated by the electro-magnet.

Referring to the drawings, 2 designates the loom frame, 3 the lay, pivoted, at 4, to the frame 2, and 5 the driving shaft mounted to rotate in suitable bearings on the frame 2. The driving shaft 5 is provided with a bevel gear wheel 6 in mesh with a similar wheel 7 on a shaft 8. The gear wheel 7 is provided with spur teeth which mesh with a spur wheel 9 on a crank shaft 10, the shafts 8 and 10 being mounted to rotate in suitable

bearings on the loom frame 2. The cranks 11 of the shaft 10 are connected to the lay 3 by arms 12, as shown, whereby during the rotation of the driving shaft 5, the lay 3 will be reciprocated in the usual manner and for the usual well known purpose.

Mounted to turn loosely on the driving shaft 5 and to move longitudinally thereon is a pulley 13 which is driven from a suitable source of power by a belt 14. The inner side of the pulley 13 has a clutch flange 15 which is adapted to engage a clutch flange 16 on the adjacent side of a brake wheel 17 which is secured on the shaft 5. The hub 18 of the pulley 13 has a circumferential groove formed therein, in which is arranged a ring 19 having projecting pins which are engaged by an arm 20 which is pivoted at 21 to a bracket on the loom frame 2. The upper end of the arm 20 is pivotally connected to one end of a rod or bar 22; and the other end of the bar 22 is pivoted to the lower arm of a lever 23 which is fulcrumed, at 24, on the loom frame 2. Encircling the bar 22 is a spring 25 one end 70 of which bears against a collar 26 secured on the bar 22 and the other end of which bears against a bracket 27 which projects from the loom frame 2.

The pressure of the spring 25 acts upon the bar 22 and arm 20 and tends to move the pulley 13 away from the wheel 17. When the pulley 13 is moved into engagement with the wheel 17 and held in engagement therewith against the action of the spring 25, 80 the power is transmitted from the pulley 13 to the driving shaft 5 and the loom is set in motion, and when the pulley 13 is moved from engagement with the wheel 17 the loom comes to a standstill and the pulley 13 turns idly on the shaft 5.

To move the pulley into engagement with the wheel 17 to set the loom in motion and to hold the pulley 13 in engagement with the wheel 17, a hand lever 28 is provided which 90 is fulcrumed, at 29, on the loom frame 2. The upper arm of the lever 28 is provided with a handle 30, and the lower arm of the lever 28 is provided with a pin 31 which projects into a slot 32 formed in the upper 100 arm of the lever 23 hereinbefore referred to. The upper end of the slot 32 terminates in a lateral socket 33 adapted to form a seat to receive the pin 31. When the upper arm 105 of the lever 28 is moved outwardly or in the 110

direction of the arrow to the position shown in Fig. 1, the pin 31 engages the wall of the slot 32 and moves the lever 23 on its fulcrum 24 and thereby moves the bar 22 in the opposite direction of the arrow against the action of the spring 25 and moves the pulley 13 into engagement with the wheel 17 as the pin 31 comes to rest in the socket 33. In this position of the parts, the pulley 13 is held against the wheel 17 by the engagement of the pin 31 with the wall of the socket 33, due to the relation of the pin 31 and socket 33, to the fulcrum points 24 and 29 of the levers 23 and 28, respectively.

When it is desired to stop the operation of the loom by hand, the same may be done by moving the upper arm of the lever 28 inwardly or reversely of the direction of the arrow, thereby disengaging the pin 31 from the wall of the socket 33, and permitting the spring 25 to move the pulley 13 from engagement with the wheel 17.

Adjacent to the levers 23 and 28 is a vertically extending rod 34 having its upper portion extending through an opening in a bracket 35 on the loom frame 2 and having its lower end pivoted to one arm of a lever 36 which is fulcrumed, at 37, on a bracket 38 on the loom frame 2. The other arm of the lever 36 is connected to one end of a brake band 39 which extends over and around and is adapted to engage the upper portion of the wheel 17 and which has its other end attached to a bracket 40 on the loom frame 2, whereby, when the rod 34 is forced upwardly, the lever 36 will draw the brake band 39 down upon the wheel 17 and stop the operation of the loom after the pulley 13 is moved from engagement with the wheel 17, as will be presently explained.

Encircling the rod 34 is a spring 41, one end of which bears against a bracket 42 on the loom frame 2 and the other end of which bears against a collar 43 secured on the rod 34 which it tends to raise. The rod 34 is held down in the position shown in the drawings, against the action of the spring 41, holding the brake band released from the wheel 17, by the wall of a notch 44 in the rod 34 engaging a pin 45 which projects into the opening in the bracket 35. The rod 34 is pressed against the pin 45 to maintain the wall of the notch 44 in engagement therewith by a flat spring 46, the lower end of which is secured to a collar on the rod 34 and the upper end of which extends into and engages the wall of the opening in the bracket 35 opposite to the pin 45. By pressing the rod 34 inwardly against the action of the spring 46 the wall of the notch 44 may be disengaged from the pin 45, thereby freeing the rod 34 and permitting it to be raised to apply the brake as previously described. The rod 34 has a bracket 47 se-

cured thereto and provided with an inclined cam face which is adapted to engage the lower arm of the lever 28 and move it outwardly to disengage its pin 31 from the wall of the socket 33, when the rod 34 is raised as just described, and thereby move the pulley 13 from engagement with the wheel 17, as previously explained, before the rod 34 is moved a sufficient distance to apply the brake 39.

The lever 36 projects forwardly from the rod 34 and its forward end is adapted to be depressed by foot power to the position shown in the drawings to release the brake 39 before the hand lever 28 is operated to engage the pulley 13 with the wheel 17. When the lever 36 is thus depressed it draws the rod 34 down against the action of the spring 41 and the flat spring 46 automatically engages the wall of the notch 44 with the pin 45 to hold the lever 36 and rod 34 depressed after the removal of the foot pressure from the lever 36.

It will thus be seen that when the parts are set in the position shown in the drawings, the loom will be set in motion, and that, thereafter, if the upper end of the rod 34 be moved to disengage the wall of the notch 44 from the pin 45, the pulley 13 will be disengaged from the wheel 17, and that, immediately thereafter the brake 39 will be applied to stop the operation of the loom.

The lay 3 is provided with the usual shuttle race 48 over which the shuttles are projected when they are shot through the separated warp threads in the usual manner; and the lay carries the usual shuttle boxes 49 at the respective ends of the shuttle race 48. The shuttle boxes are vertically movable on the lay 3 by the usual devices and in the usual manner to bring different boxes into registry with the respective ends of the shuttle race for the selection of shuttles for the usual purpose to be shot through the separated warp threads; and, as is well known, when a shuttle is present in a shuttle box, which is in registry with one end of the shuttle race 48, the shuttle box at the opposite end of the shuttle race 48 should be empty to receive the shuttle and for the prevention of a collision between two shuttles.

Each shuttle box 49 is provided with the usual pivoted arm 50 which, when no shuttle is present within the box, is held normally in an inner position, as shown at the left hand side of Fig. 3, and which, when a shuttle enters the box, is moved thereby to an outer position, as shown at the right hand side of Fig. 3.

Mounted on the breast beam 51 are two contact springs 52 which are positioned to be engaged by the arms 50 of the two shuttle boxes 49 which are in registry with the respective ends of the shuttle race 48 when 130

the arms are in the said outer position and when the lay reaches the limit of its forward movement; and which are not touched by the arms 50 when they are in the said inner position.

The arms 50 are electrically connected by a wire 53 and they are insulated from the contact springs 52. Leading from one contact spring 52 to a battery 54 is a wire 55, 10 leading from the battery 54 to an electro-magnet 56 is a wire 57 and leading from the electro-magnet 56 to the other contact spring 52 is a wire 58, thus providing an electric circuit which is normally open between the arms 50 and contact springs 52 at 15 the respective ends of the loom, and which when closed at its two open points will energize the electro-magnet 56 for a purpose presently appearing.

20 The electro-magnet 56 is mounted on a bracket on the loom frame 2 with the end of the core thereof directly beneath the outer end portion of a metal bar 59 which extends through and is slidable within a bracket 60 25 on the loom frame 2. The bar 59 projects inwardly beyond the bracket 60 and it is provided with a collar 61 between which and the bracket 60 a spring 62 encircles the bar 59 and tends to move the bar inwardly. The 30 top of the outer end portion of the bar 59 has a slight vertical movement within the bracket 60 and it is provided with a tooth 63 adapted to engage the bracket 60 and hold the bar 59 in an outer position as shown in 35 Fig. 4, against the action of the spring 62.

When the bar 59 is set in this position, and the electro-magnet 56 is energized it will draw the outer end of the bar 59 down and disengage the tooth 63 from the bracket 60 40 and permit the spring 62 to project the bar 59 inwardly. When the parts are set in the position shown in the drawings, the inner end of the bar 59 is adjacent to the rod 34; and, when the bar 59 is projected inwardly 45 it will move the rod 34 inwardly against the action of the spring 46 to disengage the wall of the notch 44 from the pin 45 and stop the operation of the loom, as previously explained. The outer end of the bar 59 is provided with a suitable handle by means of 50 which it may be set in the position shown.

The operation of the device, briefly described, is as follows:

When the loom is in motion, the parts are 55 in the position shown in the drawings; and, normally, each time the lay 3 moves toward the breast beam 51 there is a shuttle present in but one of the shuttle boxes 49 which are in registry with the respective ends of the 60 shuttle race 48 so that but one arm 50 makes contact with the adjacent contact spring 52 and the electric circuit remains open between the other contact spring 52 and the adjacent arm 50. If, however, as the lay 65 is on its beating-up stroke, during which

time the shuttle box motion operates, two shuttles should be present in the shuttle boxes 49 at the respective ends of the shuttle race 48, the arms 50 of the two shuttle boxes will make contact with the springs 52, as the lay 70 3 reaches the limit of its forward movement and before either shuttle is shot across the shuttle race 48, thereby closing the electric circuit and energizing the electro-magnet 56. The electro-magnet 56 being energized, 75 draws down the outer end of the bar 59 and frees the tooth 63 from the bracket 60 and the spring 62 projects the bar 59 inwardly, and the bar 59 engages the rod 34 and moves it from engagement with the pin 45 and 80 thereby stops the operation of the loom and the further movement of the lay 3, as previously explained, thereby avoiding a collision between the two shuttles and avoiding the consequent breaking of the warp threads. 85 After the loom has been thus stopped, the proper adjustment of the parts is effected to correct the positions of the shuttles; whereupon the bar 59 is moved outwardly by hand and its tooth 63 reengaged with the bracket 90 60, the lever 36 is then depressed by foot to reengage the rod 34 with the pin 45 to release the brake 39, and the upper arm of the hand lever 28 is moved outwardly to reengage the pulley 18 with the wheel 17 to 95 set the loom in motion, leaving the parts in the position shown for a succeeding automatic stopping operation should two shuttles again appear in the two shuttle boxes 49 at the respective ends of the shuttle race 48. 100

I claim:

1. In a loom, the combination of the frame thereof, a lay, operating means for the lay, a plurality of shuttle boxes carried by the lay and movable into registry with its shuttle race at each end thereof, a member movable to and from a set position, means to hold said member in its set position, means to move said member from its set position when released, a movable part, a spring to move said part, means to hold said part in a set position against the action of its spring, means operated by two shuttles when they are present in boxes which are in registry with the respective ends of said race to automatically release said part from its holding means, said part when released from its holding means operating to release said member from its holding means, and means operated by said member when released to 110 stop the operation of the lay.

2. In a loom, the combination of the frame thereof, a lay, operating means for the lay, a plurality of shuttle boxes carried by the lay and movable into registry with its shuttle race at each end thereof, a member movable to and from a set position, means to hold said member in its set position, means to move said member from its set position when released, a movable part, a spring to 115 120 125 130

move said part, means to hold said part in a set position against the action of its spring, electrically controlled means operated by two shuttles when they are present in boxes 5 which are in registry with the respective ends of said race to automatically release said part from its holding means, said part when released from its holding means operating to release said member from its holding means, and means operated by said member when released to stop the operation of the lay.

3. In a loom, the combination of the frame thereof, a lay, operating means for the lay, 15 a plurality of shuttle boxes carried by the lay and movable into registry with its shuttle race at each end thereof, a member movable to and from a set position, means to hold said member in its set position, means

to move said member from its set position 20 when released, a movable part, a spring to move said part, means to hold said part in a set position against the action of its spring, a normally open electric circuit, means operated by two shuttles when they are present 25 in boxes which are in registry with the respective ends of said race to automatically close said circuit, means operated by said circuit when closed to release said part from its holding means, said part when released 30 from its holding means operating to release said member from its holding means, and means operated by said member when released to stop the operation of the lay.

In witness whereof, I have hereunto set my 35 hand this 27th day of July, 1917.

CHARLES J. LONG.
